UNITED STATES PATENT OFFICE.

ANTHONY VASSELLI, OF NEWARK, NEW JERSEY, ASSIGNOR, BY MESNE ASSIGNMENTS, TO HARRIMAN NATIONAL BANK OF THE CITY OF NEW YORK, TRUSTEE.

SPRING-RETAINER.

1,350,754.

Specification of Letters Patent. Patented Aug. 24, 1920.

Application filed March 10, 1919. Serial No. 281,776.

To all whom it may concern:

Be it known that I, ANTHONY VASSELLI, a citizen of the United States, and a resident of Newark, county of Essex, and State of New Jersey, have invented a certain new and useful Spring-Retainer, of which the following is a specification.

My invention relates to device for retaining spiral coil springs in circular forms at all times during operation.

The objects of my invention are to provide means for preventing the high percentage of breakage in spiral springs during use, and to facilitate placing of such springs in operative position.

A further object of my invention is to produce a device of the character described, simple in construction, thoroughly reliable and efficient in its purpose, positive in operation, easily manufactured, and which will facilitate assembling, and be inexpensive to manufacture.

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

The invention will be first described in connection with the accompanying drawings illustrating one embodiment of my invention, wherein similar reference characters are used to designate corresponding parts throughout the several views, and then more specifically defined and indicated in the appended claims.

In positioning a spiral spring in a spring barrel, as in a motor of a talking machine, the end of the outer convolution is secured to the inner side of the rim of the barrel, and the end of the inner convolution is secured to the shaft which is to be driven, or a sleeve thereto, or to the winding shaft, as the case may be.

The diameter of the spring barrel must be greater than the coil of the spring to allow

for the fastening means by which the spring is secured to the barrel.

When the spring is released after being placed in position, it immediately expands and assumes a more or less oval form. The convolutions at the side of the coil nearest the fastening means always lie close together, while the convolutions diametrically opposite the fastening means are farther from the center of the coil. The outermost convolution opposite the point of attachment to the spring barrel is always rubbing against the side of the barrel. The strain on the spring is unevenly distributed, and the result is a large percentage of breakage occurs within an extremely short period of usage of the spring. By the use of my invention such defects and breakages are obviated.

In the drawings,

Figure 1 is a transverse section of a spring barrel with a spiral spring secured therein and my invention applied thereto, and

Fig. 2 is a perspective view of the retaining ring.

In carrying out my invention I provide a spring barrel 1 in which is secured a shaft 2. Secured to and wound upon the shaft 2 is a spiral spring 3. The outer extremity of the spring is provided with a slot 4 through which projects a staple 5, riveted or otherwise secured to the inside of the cylindrical wall of the barrel. A pin 6 is passed through the perforation of the staple beneath the end of the outer convolution of the spring and securely retains that end of the spring in position.

A ring 7 of an interior diameter, equal to that of the normal diameter of the spiral coil spring, is placed over the periphery of the spring. The ring 7 is not continuous but is provided with an opening for a short distance for the purposes hereinafter mentioned. The bulge in the end of the spring caused by the engagement of the said end with the staple 5 and the pin 6 together with such staple and pin rest within the open space between the ends of the ring member 7.

The ring 7 is of a strength sufficient to withstand the expansive force of the spring.

The outside diameter of the ring 7 is such that it will make a snug fit within the spring barrel, and the spring will be held in cir-

cular shape at all times, the strain will be equally distributed at all times, and the life of the spring will be increased as the spring cannot assume the oval shape which is the 5 direct cause of the high percentage of breakage in springs.

That part of the spring opposite the staple cannot bulge and there will be no rubbing of the outer convolution against the 10 wall of the barrel. The split ring not only retains the spring in its proper circular form but it tends to hold the pin 6 securely in position as said ring presses the end of the spring against the pin.

15 The presence of the ring 7 will greatly facilitate the assembling of the spring within the barrel as the spring will always be in condition to be handled without bulging; whereas, heretofore, without such ring 20 it was very difficult to position the spring in place in the barrel.

25 The ring 7 may be placed in position during the manufacture of the spring, it may be adjusted in place just before the spring is placed in the barrel, or it may be placed in position after the spring is in place.

30 In accordance with the provisions of the patent statutes, I have described the principle of my invention together with the apparatus which I now consider to represent the best embodiment thereof, but I desire it understood that my invention is not confined to the particular form of apparatus herein shown and described, the same being 35 merely illustrative, and that the invention can be carried out in other ways without departing from the spirit of my invention, and therefore, I claim broadly the right to employ all equivalent instrumentalities coming 40 within the scope of the appended claims, and by means of which objects of my invention are attained, and the new results accomplished, as herein set forth, as it is obvious that the particular embodiment herein 45 shown and described is only one of many that can be employed to attain these objects and accomplish these results.

Having now described my invention, what I claim and desire to secure by Letters Patent 50 ent is as follows:

1. A device of the character described, which comprises a casing, a spring wound in spiral form, one end of said spring being secured to the casing, and a permanent 55 keeper engaging the periphery of the spring and the interior surface of the casing.

2. A device of the character described, which comprises a cylindrical casing, a spring wound in spiral form within the casing, one end of said spring being secured 60 to the casing, and a permanent keeper engaging the major portion of the periphery of the spring and the inner surface of the casing.

3. A device of the character described 65 comprising a spring barrel, a shaft, a spring wound in spiral form within the barrel, one end of said spring being attached to the barrel, the other end of the spring being attached to the shaft, and a member permanently disposed between the spring and the barrel for retaining the spring in circular form, said member being unsecured to the 70 spring and barrel.

4. A device of the character described, 75 comprising a spring barrel, a shaft, a spring wound in spiral form within the barrel, means for attaching one end of the spring to the barrel, means on the shaft for attachment of the other end of the spring, and a 80 member engaging between the spring and the barrel for permanently retaining the spring in circular form.

5. A device of the character described, 85 comprising a spring barrel, a shaft, a spring wound in spiral form within the barrel, means for attaching one end of the spring to the barrel, means on the shaft for attachment of the other end of the spring, and a 90 member between the spring and the barrel, said member engaging the spring for the major portion of the outer periphery of the spring and of the inner periphery of the barrel, for retaining the spring in circular form. 95

6. A device of the character described comprising a spring barrel, a shaft, a spring wound in spiral form within the barrel, means for attaching one end of the spring to the barrel, means on the shaft for attachment of the other end of the spring, and a member between the spring and the barrel for retaining the spring in circular form; there being a gap in the member, the means lying within the gap for attaching the 100 spring to the barrel.

This specification signed and witnessed this 6th day of March, 1919.

ANTHONY VASSELLI.
